UNITED STATES PATENT OFFICE.

HARRY S. HART, OF CHICAGO, ILLINOIS.

DUMP-DOOR-OPERATING MECHANISM.

1,368,720.

Specification of Letters Patent. Patented Feb. 15, 1921.

Application filed October 21, 1918. Serial No. 258,990.

To all whom it may concern:

Be it known that I, HARRY S. HART, a citizen of the United States, residing at Chicago, in the county of Cook and State 5 of Illinois, have invented certain new and useful Improvements in Dump-Door-Operating Mechanism, of which the following is a specification.

This invention relates to operating mechanism for dump car doors.

The object of this invention is to simplify and improve operating mechanism for dump car doors in a manner to meet the requirements for successful commercial operation.

The invention is illustrated on the accompanying sheet of drawings, in which—

Figure 1 is a fragmentary side elevation of a dump car embodying my invention; 20 Fig. 2 is a transverse sectional view taken in the plane of line 2—2 of Fig. 1; and,

Fig. 3 is a transverse sectional view taken in the plane of line 3—3 of Fig. 1.

The various novel features of my invention will be apparent from the following description and drawings and will be particularly pointed out in the appended claims.

Referring to the figures of the drawings, 30 it will be noted that I have shown a dump car, the body of which includes sides 10, ends 11, and a floor 12, which in this particular instance includes stationary A-shaped portions 13 at the ends of the car 35 over the trucks which include wheels 14. These A-shaped portions include downwardly and outwardly sloping members 15 which extend from the center of the car over the center sill 16 toward the sides of 40 the car. Intermediate the ends of the car, or intermediate the trucks, the floor includes stationary sloping members 17 which extend downwardly and inwardly from the sides of the car toward the center thereof, 45 the lower edges of the member 17 terminating in longitudinal planes, including the truck wheels 14.

To normally close the dumping openings between the sides 10 of the car and the 50 lower edges of the A-shaped portion 13, I have provided vertically swinging dump doors 18, which preferably are horizontally pivotally connected along the lower edges of the sides 10 of the car. These doors 18 55 preferably are angular in shape, the upper portions thereof normally extending in a

vertical plane and the lower portions of which normally extend downwardly and inwardly toward the center of the car. Likewise, to normally close the dumping 60 openings between the center sill 16 and the lower edges of the sloping portions 17 intermediate the trucks, dump doors 19 are provided which extend downwardly and outwardly from the center sill 16 of the 65 lower edges of said sloping members 17. These dump doors 19 are pivotally connected at 20 on a horizontal pivot connection, whereby said doors may swing vertically. These doors preferably are straight 70 throughout.

This invention has to do primarily with the operating mechanism for these dump doors, the lower edges of which lie in different horizontal planes. The door operating mechanism includes an operating shaft 21 at each side of the car preferably running the full length thereof and being connected to a stationary part of the car. As shown, the operating shaft is mounted directly under the sloping floor portion 17 intermediate the trucks and extends under the lower edges of the dump doors 18 over the trucks. The operating shaft 21 on each side of the car is effective for actuating 80 the doors 18 and 19 during one operation, or, in other words, simultaneously. The operating connection between the operating shaft 21 and the dump doors 18 includes spaced arms 22 which are rigidly fixed to 85 the operating shaft 21, there being a pin 23 extending between the outer ends of said arms. A link 24, one end of which is pivotally connected to a bracket 25 secured to the lower portion of the door 18, is pivotally connected to the arm 22 by a loose or sliding connection, including a slot 26 in the link 24 which slidably receives the pin 23 connecting the spaced arms 22. It will be noted that the link 24 is provided with 90 a square locking notch 27, which, when the door 18 is closed, as shown at the left-hand side of Fig. 2, receives the upper half of the operating shaft 21 for locking the side dump door 18 in locked position. To 95 unlock the door 18 and move it into an open position, the shaft 21, as shown at the left-hand side of Fig. 2, is rotated in a counterclockwise direction, which causes the arm 22 rigidly connected therewith to move 100 in the same direction, whereupon the pin 23 moves downwardly in the slot 26 and

gradually forces the link 24 into a position beyond the upper edge of the shaft for freeing the door 18, which, under the weight of the load in the car, moves outwardly into an open position. Assuming, however, that there is no load in the car, the door 18 will be moved outwardly as a result of an outward thrust transmitted through the arms 22, which, when they 10 reach an outward horizontal limiting position, cause the door to be completely opened, as shown at the right-hand side of Fig. 2. In closing the door the shaft is moved in an opposite direction, which 15 causes the link 24 to be drawn inwardly, tightly pressing the lower edge of the door 18 in engagement with the lower edge of the sloping portions 15 of the A-shaped floor to form a positive seal against leaks, 20 the last portion of the rotating movement of the shaft causing the link 24 to move into a locking relationship with respect to the operating shaft for locking the door in closed position.

25 By referring to Fig. 3, it will be noted that the operating connection between the operating shaft 21 and its associated intermediate dump doors 19 includes spaced arms 28 rigidly connected to the operating shaft 30 and being connected at their outer ends by a pin 29, which is received in a slot 30 in one end of the relatively long link 31, which connects the arms 28 with the lower edges of the dump doors 19. Each of the links 31 35 intermediate its length is provided with a locking notch 32 which, when the door is in closed position, hooks over the shaft 21 for locking the dump doors 19 in locked position. The left-hand dump door or doors in 40 Fig. 3 are in such locked position. To unlock said doors and open the same, the operating shaft shown at the left-hand side in Fig. 3, is moved in a counterclockwise direction, which first causes the notched portion of the link 31 to disengage the shaft 21, the link 31 being moved about its lower end as a pivot. As soon as the notch is moved 45 out of operating association with the shaft, the dump doors 19 are swung into an open position as a result of the load in the car. Assuming, however that there is no load being dumped, the dump doors 19 will be positively opened by the inward thrust transmitted thereto by the arm 28, the doors 19 50 finally assuming an open position, as shown at the right-hand side of Fig. 3, in which case the arms 28 and links 31 lie substantially in the same plane. To close the dump doors 19 the shaft is moved in the opposite direction, whereupon the doors are swung outwardly until their lower edges make a tight sealing joint with the lower edges of the floor members 17, the last portion of the 55 rotative movement of the operating shaft causing the locking notch of the links 31 to

hook over the operating shaft 21 for locking the dump doors 19 in closed position.

It will be understood that when the operating shaft on either side of the car is actuated, the doors over the trucks and intermediate the trucks are simultaneously actuated.

It is my intention to cover all modifications of the invention falling within the spirit and scope of the following claims.

I claim:

1. In a dump car, the combination of a plurality of normally inclined vertically swinging dump doors over and between the trucks, an operating shaft mounted on a stationary part of the car at the side thereof, arms rigidly connected to said shaft, and links connecting said arms with said doors whereby the latter may be operated.

2. In a dump car, the combination of a plurality of normally inclined vertically swinging dump doors over and between the trucks, an operating shaft mounted on a stationary part of the car at the side thereof, arms rigidly connected to said shaft, and links connecting said arms with said doors whereby the latter may be operated and the locking condition of said doors changed.

3. In a dump car, the combination of a plurality of normally inclined vertically swinging dump doors over and between the trucks, an operating shaft mounted on a stationary part of the car at the side thereof, arms rigidly connected to said shaft, and links connecting the arms with said doors whereby the latter may be moved into closed position.

4. In a dump car, the combination of a plurality of normally inclined vertically swinging dump doors over and between the trucks, an operating shaft mounted on a stationary part of the car at the side thereof, arms rigidly connected to said shaft, and links connecting the arms with said doors whereby the latter may be moved into closed position, said links having portions coöperating with said shaft for locking the doors in closed position.

5. In a dump car, the combination of pivotally mounted dump doors, the doors over the trucks extending downwardly and inwardly and the doors intermediate the trucks extending downwardly and outwardly, an operating shaft for said doors, and operating connections including rigid links between said shaft and said doors for actuating the latter.

6. In a dump car, the combination of pivotally mounted dump doors, the doors over the trucks extending downwardly and inwardly and the doors intermediate the trucks extending downwardly and outwardly, an operating shaft for said doors, and operating connections including rigid links between said shaft and said doors for actu-

ating the latter and for changing their locking condition.

7. In a dump car, the combination of a plurality of vertically swinging dump doors, those over the trucks extending downwardly and inwardly and those intermediate the trucks extending downwardly and outwardly, an operating shaft, and operating connections between said shaft and said doors including rigid links whereby said doors may be actuated, said links having locking portions which coöperate with said operating shaft for locking said doors in closed position.

15 8. In a dump car, the combination of a plurality of vertically swinging doors, the doors over the trucks extending downwardly and inwardly and the doors between the trucks extending downwardly and outwardly, said doors having their swinging edges in different horizontal planes, an operating shaft, and connections between said operating shaft and the lower edges of said doors for moving the swinging edges of said doors into closed position.

9. In a dump car, the combination of a plurality of vertically swinging doors, the doors over the trucks extending downwardly and inwardly and the doors between the trucks extending downwardly and outwardly, said doors having their swinging edges in different horizontal planes, an operating shaft, and connections between said operating shaft and the lower edges of said doors for moving the swinging edges of said doors into closed position and for locking the said doors in closed position.

10. In a dump car, the combination of a normally inclined vertically swinging dump door over a truck, an operating shaft mounted on a stationary part of the car inwardly from a side thereof, an arm rigidly connected to the shaft, and a link connecting the arm and door whereby the latter may be operated.

11. In a dump car, the combination of a normally inclined swinging dump door over

a truck, an operating shaft mounted on a stationary part of the car, an arm rigidly connected to said shaft, and a link connection 50 between said arm and door whereby the latter may be operated.

12. In a dump car, the combination of a normally inclined swinging dump door over a truck, an operating shaft mounted on 55 a stationary part of the car, an arm rigidly connected to said shaft, and a link connection between said arm and door whereby the latter may be operated, said link having a locking portion for engaging the shaft to 60 lock the door in a given position.

13. A car of the class described having sides and ends, the floor over the trucks comprising portions sloping downwardly and outwardly toward the sides of the car, 65 outwardly swinging doors pivoted to the sides of the car coöperating with said stationary floor portions, the floor between the trucks comprising downwardly and inwardly extending stationary portions, downwardly and inwardly swinging doors pivoted at or near the center sill, coöperating with said downwardly and inwardly extending floor portions, an operating shaft, and connections from said operating shaft to the 75 downwardly and inwardly swinging doors for simultaneously operating the doors.

14. A car of the class described having sides and ends, the stationary floor portion over the trucks arranged to discharge the 80 load downwardly and outwardly, the stationary floor portions between the trucks adapted to discharge the load downwardly and inwardly, downwardly swinging doors coöperating with said first named floor portions and inwardly swinging doors coöperating with the last named floor portions, and operating mechanism for simultaneously operating the downwardly and inwardly swinging doors.

Signed at Chicago, Illinois, this 18th day of October, 1918.

HARRY S. HART.
